Inventor
Solomon Chervin.
O. W. Andersonson

Attorney

UNITED STATES PATENT OFFICE.

SOLOMON CHERVIN, OF SAN FRANCISCO, CALIFORNIA.

WINDOW.

Application filed October 21, 1921. Serial No. 509,351.

To all whom it may concern:

Be it known that I, SOLOMON CHERVIN, a citizen of the United States, resident of San Francisco, in the county of San Francisco and State of California, have made a certain new and useful Invention in Windows; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a face view of the window, with parts in section and parts broken away, and showing only a single sash cord of the duplicate cords for each sash.

20 Figure 2 is a vertical section of the window casing, showing the sashes in full lines and as tilted, the sash cords and pulleys being omitted.

Figure 3 is a detail side view of a spring pin and adjacent parts.

25 Figure 4 is a detail section of a sash pivot.

Figure 5 is a section on the line 5—5, Figure 1.

Figure 6 is a detail perspective view of a channel bar.

30 Figure 7 is a similar view of one of the metal plates.

Figure 8 is a similar view of a spring pin.

The invention has relation to windows of ordinary wooden construction, used in non-fireproof buildings, and has for an object the provision of improved means attachable to new or old windows, whereby each window sash may be swung inward pivotally for cleaning or ventilating purposes, each 40 sash being also slidable upwardly and downwardly and being counterbalanced as usual.

The invention consists in the novel construction and combinations of parts, as hereinafter set forth.

45 In the accompanying drawings illustrating the invention, the numeral 1 designates the window frame, and 2 and 3 the upper and lower sashes, having respectively the usual duplicate sash cords 4 and 5, passing upwardly over pulleys 6 and 7, said cords having the usual counterweights at their outer ends.

50 8 is a channeled supplemental stile of flat metal having opposite parallel flanges 9 and 55 open at its outer side and of a breadth and

thickness suitable to slide vertically in the guideway 10 or 11 of the window frame, and of a length equal to the length of the sash stile. One of these supplemental stiles is secured to each sash stile through the medium of a pivot bolt 12, engaging a lower perforation 12' of said supplemental stile, and having threaded engagement at 13 with a boss 14 of a metal plate 15, the latter fitting in a lower lateral recess 16 of the sash stile and affording a longer and more secure bearing for the said pivot bolt. This pivot bolt is also utilized as a means of attachment of the end of the sash cord 4 or 5, a washer 17 being interposed between the head 18 of said bolt and the said cord, and serving to clamp the sash cord between the same and the respective supplemental stile, to thereby take the strain of the weight of the sash from the pivot bolt 12. The head 18 of said bolt, the washer 17 and the sash cord are all located within the channel 8' of the supplemental stile so that they will not scrape against or frictionally engage the wall of the guideway 10 or 11 in which 60 65 70 75 80 85 90 95 100 105 110 said stile slides.

In the application of the supplemental stile 8 to windows already in place in buildings, each sash is planed down at each side thereof or at the outer side of each stile, to an extent equal to the thickness of the supplemental stile, namely for about one half inch, this thickness being also equal to that of the removable beads or molding strips 19 and 20 forming the inner and middle walls of the guideways 10 and 11 in which the sashes slide, said beads or strips serving to hold the sashes in place ordinarily, but in the present instance serving to hold the supplemental stiles 8 in place in the guideways 10 and 11. In this way, the lower sash is free to swing vertically upon the pivot bolt 12, past and without interference with the vertical strip 19, of the window frame, and similarly the upper sash is free to swing pivotally upon its bolt 12 past and without interference with the vertical strip 20, the supplemental stiles 8 of each sash remaining in place in the guideways 10 and 11, wherein they slide upwardly and downwardly with the sashes, being carried along therewith.

In order to retain the sashes normally parallel or in the planes of the respective supplemental stiles 8, each sash is provided

at each side thereof with a spring pin 21, engaging an upper perforation 22 of the stile of the sash, and normally engaging also an upper perforation 23 of the supplemental stile related thereto.

Upon pulling out or disengaging the spring pins 21 of either sash from the supplemental stiles, the sash may be swung pivotally, as shown in Figure 2 of the drawings, for cleaning or other purpose, and upon reversely swinging the sash, the spring pins thereof may again become engaged with the upper perforations of the supplemental stiles 8.

15 The invention is of simple and practical nature, readily applicable to new windows or those already installed.

I claim:—

In a window construction, having a sash

therein, the combination with a stile of said sash having a lateral recess, of a channeled supplemental stile having a perforation, a plate disposed in said recess and having an inwardly extending boss disposed in a reduced portion of said recess, a pivot bolt disposed in said perforation and having threaded engagement with said boss, a sash cord engaging said pivot bolt and located within the channel of the supplemental stile, and a washer engaging said bolt and clamping said sash cord between the same and said supplemental stile.

20 In testimony whereof I affix my signature in presence of two witnesses.

25 SOLOMON CHERVIN.
